CLIP-ON HEARING AID

Kim Yamasaki, Chicago, Ill., assignor to Beltone Hearing Aid Company, Chicago, Ill., a corporation of Illinois

Filed Jan. 3, 1961, Ser. No. 63,419

Term of patent 14 years

(Cl. D26—14)

FIGURE 3 is an elevational view of the other side of a clip-on hearing aid, showing my new design;

I claim:

The ornamental design for a clip-on hearing aid, substantially as shown.
